(57) **CLAIM**

The ornamental design for a duct for refrigerator as shown and described.

DESCRIPTION

FIG. 1 is a front perspective view of a duct for refrigerator showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of the area ‘8’ as identified in FIG. 1;

FIG. 9 is a partial enlarged view of the area ‘9’ as identified in FIG. 1;

FIG. 10 is a cross-sectional view taken along line 10-10 in FIG. 2;

FIG. 11 is the cross-sectional view of FIG. 10 shown in an environment of use with attached shelves for a refrigerator;

FIG. 12 is a front view of the duct for refrigerator shown in a second environment of use installed inside a refrigerator;

FIG. 13 is a front view of the duct for refrigerator shown in a third environment of use installed inside a refrigerator with attached shelves; and,

FIG. 14 is a front view of the duct for refrigerator shown in a fourth environment of use installed inside a refrigerator with attached shelves.

(Continued)

The portions of FIGS. 11-14 drawn in broken lines show environmental structure only and form no part of the claimed design. The dash-dot-dash spaced broken lines in FIGS. 1, 8 and 9 are for the purpose of annotating the enlarged view only and form no part of the claimed design.
